[57] CLAIM

The ornamental design for a combined carbon monoxide detector, alarm and garage door opener, as shown and described.

DESCRIPTION

FIG. 1 is a front elevational view of the combined carbon monoxide detector, alarm and garage door opener of the present invention;

FIG. 2 is a rear elevational view of the combined carbon monoxide detector, alarm and garage door opener of FIG. 1; FIG. 3 is a left side elevational view of the combined carbon monoxide detector, alarm and garage door opener of FIG. 1; FIG. 4 is a right side elevational view of the combined carbon monoxide detector, alarm and garage door opener of FIG. 1;

FIG. 5 is a top plan view of the combined carbon monoxide detector, alarm and garage door opener of FIG. 1; and, FIG. 6 is a bottom plan view of the combined carbon monoxide detector, alarm and garage door opener of FIG. 1.
